US00D862927S

(12) **United States Design Patent** (10) **Patent No.:** **US D862,927 S**
(45) **Date of Patent:** **** Oct. 15, 2019**

(54) **MAT ASSEMBLY**

(71) Applicant: **John Levin**, Beverly Hills, CA (US)

(72) Inventor: **John Levin**, Beverly Hills, CA (US)

(**) Term: **15 Years**

(21) Appl. No.: **29/630,301**

(22) Filed: **Dec. 20, 2017**

(51) LOC (12) Cl. **06-11**

(52) U.S. Cl.

USPC **D6/588**; D6/592

(57) **CLAIM**

The ornamental design for a mat assembly, as shown and described.

DESCRIPTION

FIG. 1 is a front top right isometric view of a mat assembly design showing my new design;

FIG. 2 is a front top right isometric view of the mat assembly, in an exploded position;

FIG. 3 is a front bottom left isometric view of the mat assembly;

FIG. 4 is a front bottom right isometric view of the mat assembly;

FIG. 5 is a front elevational view of the mat assembly;

FIG. 6 is a top plan view of the mat assembly;

FIG. 7 is a left elevational view of the mat assembly;

FIG. 8 is a right elevational view of a mat assembly;

FIG. 9 is a bottom plan view of the mat assembly;

FIG. 10 is a rear elevational view of the mat assembly;

FIG. 11 is a rear top left isometric view of the mat assembly;

FIG. 12 is a rear top right isometric view of the mat assembly;

FIG. 13 is a rear bottom right isometric view of the mat assembly; and,

FIG. 14 is a rear bottom left isometric view of the mat assembly.

1 Claim, 14 Drawing Sheets
